CLAIM

The ornamental design for a magnetic card reader and door knob assembly, as shown and described.

DESCRIPTION

FIG. 1 is a front elevational view of a magnetic card reader and door knob assembly showing our new design;
FIG. 2 is a left side elevational view thereof, the right side being a mirror image of that shown;
FIG. 3 is a top plan view thereof;
FIG. 4 is a top, front, and left side perspective view thereof;
FIG. 5 is a front elevational view of a second embodiment of a magnetic card reader and door knob assembly showing our new design;
FIG. 6 is a left side elevational view thereof, the right side being a mirror image of that shown;
FIG. 7 is a top plan view thereof; and,
FIG. 8 is a top, front, and left side perspective view thereof.
